UNITED STATES PATENT OFFICE.

GEORGE P. TILTON, OF NEWBURYPORT, MASSACHUSETTS, ASSIGNOR TO
THE TOWLE MANUFACTURING COMPANY, OF SAME PLACE.

DESIGN FOR A SPOON.

SPECIFICATION forming part of Design No. 20,733, dated May 19, 1891.

Application filed April 18, 1891. Serial No. 389,509. Term of patent 7 years.

To all whom it may concern:

Be it known that I, GEORGE P. TILTON, of Newburyport, Massachusetts, have invented a Design for Spoons, of which the following 5 is a full, clear, and exact description.

Reference is to be had to the accompanying drawing, forming a part of this specification, in which the figure represents a face view of a spoon embodying my new design.

10 The leading feature of my design consists in the handle ornamentation, the same including the representation of the "Liberty Bell," arranged in connection with the representation of an eagle standing on the bell support 15 or beam.

The letter *a* indicates the representation of the bell, *b* the eagle, and *c* the beam or frame from which the bell is suspended, the eagle appearing with spread wings and

perched on the bell-support. Above such 20 figures appear the numerals "1776," and below the figures the word "Philadelphia" appears; but such numerals and name form no part of my design. In connection with such handle ornamentation the bowl ornamentation shown is arranged, the same consisting 25 of the representation of "Independence Hall," (indicated by the letter *d*), and below the same a ribbon figure *e* appears bearing the name "Independence Hall." The name, however, 30 forms no part of the design.

I claim—

The design for spoons herein shown and described.

GEO. P. TILTON.
